UNIT FRAME FOR DEMOUNTABLE LOAD-BODIES

Thomas W. Blasingame, P.O. Box 153,
Boise, Idaho 83702

Filed Aug. 8, 1974, Ser. No. 488,102

Term of patent 14 years

Int. Cl. D12—76

U.S. Cl. D12—96

FIG. 1

FIG. 2

FIG. 3

FIG. 1 is a right rear perspective view of a unit frame for demountable load-bodies embodying my new design. FIG. 2 is a left front perspective view thereof.

FIG. 3 is a side elevational view thereof with a load body and tractor and chassis shown in exploded view and in broken lines for illustrative purposes only.

I claim:

The ornamental design for a unit frame for demountable load-bodies, substantially as shown.
